UNITED STATES PATENT OFFICE.

PAUL D. PHILLIPS, OF CHICAGO, ILLINOIS, ASSIGNOR TO BENJAMIN ELECTRIC MFG. COMPANY, OF CHICAGO, ILLINOIS, A CORPORATION OF ILLINOIS.

ATTACHMENT-PLUG.

1,236,210.

Specification of Letters Patent. Patented Aug. 7, 1917.

Application filed May 12, 1913. Serial No. 767,049.

To all whom it may concern:

Be it known that I, PAUL D. PHILLIPS, a citizen of the United States, residing at Chicago, in the county of Cook and State 5 of Illinois, have invented new and useful Improvements in Attachment-Plugs, of which the following is a full, clear, concise, and exact description, reference being had to the accompanying drawing, forming a part of 10 this specification.

My invention pertains to attachment plugs, and particularly to attachment plugs of the kind in which the threaded contact is made rotatable with respect to the remainder of 15 the plug. It is the principal object of my invention to improve upon the construction of the threaded contacts of attachment plugs, and to provide an effective and economical manner of securing insulating 20 thumb rings to such contacts.

An embodiment of my invention, as applied to a separable attachment plug having a rotatable threaded contact on the insertible portion thereof, is described, by way 25 of example, in the following specification and shown in the accompanying drawings. It is to be understood, however, that the invention may be applied to other types of plug than that described and shown, and 30 that changes may be made in the embodiment which I have chosen as illustrating my invention, without exceeding the scope of the invention, as defined in the appended claims.

35 In the drawings:

Figure 1 is a longitudinal section through a separable attachment plug constructed in accordance with my invention;

Fig. 2 is a section on the line 2—2 of 40 Fig. 1, looking in the direction of the arrows;

Fig. 3 is a top plan of the insertible portion of the plug;

Fig. 4 is a bottom plan of the same;

Fig. 5 is a horizontal section, taken on the line 5—5 of Fig. 1, looking in the direction of the arrows;

Fig. 6 is a top plan of the binding-terminal carrying portion of the plug;

Fig. 7 is a bottom plan of the same;

Fig. 8 is a perspective detail view of one of the forked contacts of the insertible portion; and

Fig. 9 is a perspective detail view of one of the plunger contacts of the binding-terminal carrying portion. 55

Like reference characters refer to like parts throughout the following specification and the several figures of the accompanying drawings. 60

Referring now particularly to Figs. 1—5 and Fig. 8, the insertible portion of the plug includes an insulating base 10 having, at its lower end, an enlargement 11, the upper surface of which enlargement forms a shoulder 12. The base 10 has formed therein a pair of chambers 13 containing forked connecting contacts 14, such contacts being held in place by means of screws 15 and 16, respectively, passing longitudinally through 70 the base. The forked contacts 14 are formed with surface threads on their inner sides, which threads are engaged by the screws 15 and 16. The forked contacts fit closely within the chambers 13, which enables them 75 to be securely retained in position in this manner. The center contact, 17, of the plug is clamped against the upper end of the base 10 by the head of the screw 16, such center contact thus being in electrical connection with one of the forked connecting 80 contacts 14.

Rotatably mounted on the base 10 is a threaded contact, which comprises a metallic threaded shell 18 having, at its upper end, 85 an inwardly-extending flange 19 the edge of which slidingly embraces the top end of the base 10. At its lower end, the shell 18 is formed with a longitudinally fluted neck 20 which engages within an upwardly extending 90 flange 21 of an insulating thumb ring 22. The inside of the flange 21 is longitudinally fluted in a manner corresponding to that in which the neck 20 is fluted, so that a firm non-rotatable mechanical connection is 95 established between the shell 18 and the thumb ring 22. The thumb ring 22 is formed with an inwardly extending annular collar 23, on the top face of which the neck 20 of the shell 18 rests. The collar 23 slid- 100

ingly embraces the base 10, and slidingly rests upon the shoulder 12 of the extension 11 of the base 10. Longitudinal withdrawal of the threaded contact from the base is prevented by means of a metallic disk 24 which lies upon the upper end of the base 10, being clamped in position by the screw 15. The edge of the disk 24 slidingly engages the top surface of the flange 19 of the shell 18, thereby preventing withdrawal of the threaded contact and establishing electrical connection between the latter and the second forked connecting contact 14.

My improved construction of threaded contact, in which a non-circular portion of the shell coöperates with a corresponding non-circular portion of the thumb ring is exceedingly economical of construction, and does away with the expensive molding and other connecting operations which have heretofore been resorted to in connecting the shell with the thumb ring. In the embodiment of my invention which I have described, the thumb ring may be formed by the ordinary pressing operation, and the shell may be formed by a simple spinning and stamping operation. All that is then necessary is to press the shell into the thumb ring. The fit of the parts is close enough to prevent any undesirable play between them; and accidental removal of the shell from the thumb ring is effectually prevented by reason of the engagement of the collar 23 of the thumb ring with the shoulder 12 and the engagement of the flange 19 of the shell with the disk 24.

The insertible portion of the plug includes a base 25, having secured to the upper surface thereof a pair of binding plates 26. These binding plates are bent at right angles so as to form a pair of plunger contacts 27, each of which engages one of the forked contacts 13. The plunger contacts 27 are formed with internally threaded slots 28 at their lower parts, which slots receive cap screws 29 which pass upwardly through the base 25 (Figs. 1, 2, 6 and 9). The binding plates 26 lie snugly in correspondingly shaped depressions 30 formed in the top surface of the base 10, so that the screws 29, entering the slots 28 as described above, are sufficient to retain the binding plates firmly in position. Conductors are led to the binding plates 26 through apertures 31 formed longitudinally through the base, and are clamped against withdrawal by means of a conductor-gripping bushing 32, whereby the binding plates are relieved from all strain.

Having thus fully described my invention, what I claim as new and desire to secure by Letters Patent is:

1. An attachment plug comprising, the combination with an insulating base, of a

threaded contact rotatably mounted on said base, an insulating thumb ring, said ring and contact having inter-engaging means freely engageable and disengageable by relative longitudinal movement but preventing their relative rotation, and means engaging 70 said contact and ring to prevent their disengagement by relative longitudinal movement, comprising an abutment supported by said base adjacent the entering end of the plug engaging the threaded contact. 75

2. An attachment plug comprising, the combination with an insulating base, of a threaded contact rotatably mounted on said base, an insulating thumb ring, said ring and contact having inter-engaging longitudinal 80 corrugations freely engageable and disengageable by relative longitudinal movement but preventing their relative rotation, and means engaging said contact and ring to prevent their disengagement by relative 85 longitudinal movement, comprising an abutment supported by said base adjacent the entering end of the plug engaging the threaded contact.

3. An attachment plug comprising the 90 combination with an insulating base, of a threaded contact rotatably mounted on said base, an insulating thumb ring, said ring and contact having interengaging means freely engageable and disengageable by relative 95 longitudinal movement but preventing their relative rotation, and means engaging said contact and ring to prevent their disengagement by relative longitudinal movement comprising an abutment of conducting 100 material supported by said base adjacent the entering end of the plug engaging the threaded contact, and an electrical contact electrically connected with said abutment. 105

4. An attachment plug comprising the 105 combination with an insulating base, of a threaded contact rotatably mounted on said base, an insulating thumb ring, said ring and contact having interengaging means freely engageable and disengageable by relative longitudinal movement but preventing their relative rotation, and means engaging 110 said contact and ring to prevent their disengagement by relative longitudinal movement, comprising a flange supported by said 115 base adjacent the entering end of the plug engaging the threaded contact.

5. An attachment plug comprising the combination with an insulating base, of a threaded contact rotatably mounted on said 120 base, an insulating thumb ring, said ring and contact being sleeved one upon the other and freely engageable and disengageable from each other by relative longitudinal movement, interengaging means on said 125 ring and contact brought into engagement when the ring and contact are assembled for preventing relative rotation therebe-

tween, said contact and ring being each provided with an abutment, said base being provided with two abutments one engaging the contact abutment and the other engaging the 5 ring abutment for preventing separation of said ring and contact by relative longitudinal movement.

In witness whereof, I have hereunto subscribed my name in the presence of two witnesses.

PAUL D. PHILLIPS.
